United States Patent Office.

HENRY WHITEHOUSE, OF NEWARK, NEW JERSEY

Design No. 3,920, dated March 22, 1870.

DESIGN FOR A SET OF TURRET AND RINGS FOR HARNESS-SADDLES.

The Schedule referred to in these Letters Patent and making part of the same.

To all whom it may concern:

Be it known that I, HENRY WHITEHOUSE, of Newark, in the county of Essex and State of New Jersey, have originated and designed a new Turret-Ring and Hook, composing a set for harness, of which the following is a full, clear, and exact description, reference being had to the accompanying drawings making part of this specification.

The nature of this invention is a new and tasteful design for a set composed of a pair of turret-rings and a hook for harness, as fully portrayed in the accompanying drawings, where—

Figure 1 represents one of the pair of turret rings, and

Figure 2, the hook.

It will be observed that the general design consists

of perpendicular sides *a a*, angular base *c*, curved interior of crown *d*, and the exterior of crown formed of two arcs of circles *e e*, meeting at a common center, *f*, with projecting points or horns *g g*, as shown in fig. 1.

The harness ornaments after my design may be covered with leather, lined or not, at pleasure.

Having thus described my invention,

What I claim as new, and desire to secure by Letters Patent, is—

The design for a set of turret-rings and hook for harness, as herein shown and described.

HENRY WHITEHOUSE.
